UNITED STATES PATENT OFFICE

155,883

DESIGN FOR A DISPLAY BOX

Abraham Fogel, Montreal, Quebec, Canada

Application February 15, 1946, Serial No. 126,577

Term of patent 14 years

(Cl. D80—5)

To all whom it may concern:

Be it known I, Abraham Fogel, a subject of the King of Great Britain, resident of Montreal, in the Province of Quebec and Dominion of Canada, have invented a new, original, and ornamental Design for Display Box, of which the following is a specification, reference being had to the accompanying drawing, forming part thereof.

In the drawing:

Figure 1 is a perspective view of a display box, showing my new design;

Figure 2 is a top plan view thereof;

Figure 3 is a side elevation;

Figure 4 is an end elevation;

Figure 5 is an exploded perspective view; and

Figure 6 is a horizontal sectional view thereof taken on the line 6—6 of Figure 3.

The characteristic feature of my design resides in the combination on the box disclosed of the parallel rows of equi-spaced, substantially square shaped protuberances on two of the faces adjacent to the corners and extending throughout the depth of the transparent cover in association with a flanged opaque base of limited depth, all as shown.

I claim:

The ornamental design for a display box, as shown and described.

ABRAHAM FOGEL.
